METALLIC ROOFING.

No. 508,193.

Patented Nov. 7, 1893.

UNITED STATES PATENT OFFICE.

JOSEPH TYRA, OF MINNEAPOLIS, MINNESOTA.

METALLIC ROOFING.

SPECIFICATION forming part of Letters Patent No. 508,198, dated November 7, 1893.

Application filed June 20, 1892. Serial No. 437,244. (No model.)

To all whom it may concern:

Be it known that I, JOSEPH TYRA, a citizen of the United States, residing at Minneapolis, in the county of Hennepin and State of Minnesota, have invented certain new and useful Improvements in Metallic Roofing; and I do hereby declare the following to be a full, clear, and exact description of the invention, such as will enable others skilled in the art to 10 which it appertains to make and use the same.

My invention relates to metallic roofing. It was especially designed for use in connection with copper plate roofing, with a view of constructing the roof surface entirely of 15 copper and holding the same in place, without the use of nails or screws on its shedding surfaces. To this end, I employ raised joint strips which are rigidly secured in position, by bolts or otherwise, crosswise of the rafters, or roof-framing and underlie the lower margin of the upper member of each pair of interlocking plates; and I hold the plates to the 20 strips by means of copper cleats or straps, which embrace the strips and have their free 25 ends interlocking with the upper margin of the lower member of each pair of interlocking plates. The plates themselves are jointed over the upper lower margin or at the back of the strips. When thus arranged, the copper 30 cleat will then hold both interlocked plates to the strips, one branch of the cleat serving to hold the plates down flat against the rafters or roof-framing, and the other branch of the cleat to hold the said plates 35 from slipping downward on the roof. The raised joint strips are preferably made of wood and are wedge shaped in cross section. When thus constructed all parts of the copper-plates rest on a solid bed. In case however, 40 it is desired to make a perfectly fire-proof roof the joint strips may be constructed of iron; and in that case, to save material, they would be of angular form, the foot part of which would rest on the rafters, and the 45 raised part or flange would underlie the lower margin of the upper plate. The strips are preferably bolted to the roof framing; and there may be provided for co-operation therewith, tie-bars or tie-strips underneath the 50 rafters arranged parallel with the joint strips

and bolted together therewith through the roof framing. This latter construction strengthens the roof and assists to hold any filling material, which may be employed between the rafters, such for example, as fire-proofing tiles. 55

My invention is illustrated in the accompanying drawings, wherein, like letters referring to like parts throughout, Figure 1 is a perspective view looking from the left toward one angle of the roof, some parts being 60 broken away and others shown in section. Fig. 2 is a detail in end view or section, showing the strip (wooden) cleat, and interlocking plates as they appear after the joint is formed, the said parts being shown detached from the 65 roof. Fig. 3 is a similar view to Fig. 2, in which the interlocking parts of the cleat E and the plates B and B' are only partially folded or rolled together. Fig. 4 is a plan view of one of the wooden strips and the cleat. Fig. 70 5 is a cross section of the same. Fig. 6 is a view in section, showing a slight modification of the construction shown in Fig. 1, wherein tacks are employed, to hold the cleat to the strip. Fig. 7 is a sectional elevation showing 75 a modified construction of the strip. Fig. 8 is a similar view of the modified strip detached from the rafters. Fig. 9 is a plan view of the construction shown in Fig. 8. Fig. 10 is a view in vertical section, taken on the 80 line X X' of Fig. 2, some parts being broken away.

A represents a part of one of the roof rafters.

B B' represent respectively, the upper and 85 lower members of the pairs of interlocking plates, constituting the metallic roofing. These plates are made of copper, as before stated, and interlock at their joints, by hook or fold flanges. 90

C represents the wedge-shaped wooden strips, which are rigidly secured to the roof framing, by bolts C'. These bolts are countersunk in the wooden strips, and may either work through holes in the rafters, or through 95 holes in the filling, if such be employed between the rafters. As shown, they work through the rafters.

D represents the tie-strips underneath the rafters parallel with the joint strips, to which 100

the same are bolted. Instead of the tie-strips washers may be employed between the nut and the under surface of the rafters for filling material. Otherwise, than on the ground 5 of expense, tie-strips are preferable, in virtue of the additional strength for trussing action added to the roof.

Is the copper cleat, which loosely embraces the joint strip, as shown in all the figures, except Fig. 6, and has its free ends *e* spread apart and formed with down-turned flanges engaging the up-turned margin of the roof sheet B'. In constructing the roof, the plates B' are banked with their up-turned upper 15 margins against the back or vertical face of the strip, after the cleat has been placed on the strip. The free ends of the cleat are then bent down over the back turned edge of the plate B'. The plate B is then placed in position with the lower or inclined part of the same, extending over the top of the strip and hooking under the back turned flange on the plate B', thus overlying the cleat. The engaging flanges are then turned down, as shown 20 in Figs. 2, 6 and 7 of the drawings, forming a tight joint, at the upper lower margin of the strip. When the joint is thus formed, it is obvious, that the plates will be held together and locked to the strip. One of the 25 arms of the cleat will hold the roof plate from rising, and the other from slipping downward. As this cleat is made of copper, it will, of course last as long as the copper roof plate, and the whole constitutes a roofing which 30 will last indefinitely. Inasmuch as the joint between the upper and lower members of the interlocking plates is formed at the eave or back of the strip as described, no water or snow could enter under the plates, even if 35 the joints should open or unfold more or less under the action of contraction or expansion.

In the construction shown in Figs. 7, 8 and 9, an angle iron strip F is employed as a substitute for the wooden strip C, shown in the 45 other figures. In all other respects, the construction is the same. The use of the angle-iron strip, instead of the wooden strip, would be simply to make the roof absolutely fire-proof.

50 In the construction shown in Fig. 6, the cleat E is shown as tacked by a copper nail G, to the back of the strip; and if so desired, a similar tack might be applied to the upper arm of the cleat, extending into the face of 55 the wooden strip. Inasmuch, however, as these tacks would be under the roof-plates, no harm could arise from their use, even if they should become loose or rust out. Of course, if copper tacks were employed they 60 would not rust out but might come loose. These tacks would hardly be necessary or of any particular service, after the roof was laid, but would be of convenience in laying the roof, making it easier to form the joint. I 65 contemplate using a single cleat for each pair of interlocking roof plates, if the plates be

short, and two or more, if the plates be long. It will of course be understood, that as many may be used as are required to securely hold the roof-plates in position.

70 By constructing the rafters of iron and using the metallic form of the joint strip, as shown at F, in Figs. 7, 8 and 9, my construction affords an absolutely fire-proof roof. If desired to give greater solidity to the roof top, a filling of fire-proof tiling or other similar material (not shown) may be placed between the rafters.

75 The great advantage of this roof is, that when it is laid the shedding surfaces are absolutely without perforations or joints, which can open to admit the water or the snow, under the plates, and the fastenings are of such a character, that they cannot become loose by the corrosive action of rust or under the action of contraction or expansion of the metal plates. When made of copper, as described, such a roof will outlast any building to which it may be applied.

80 It is of course obvious, that the invention is equally applicable to a metallic roof of any kind, whether made of copper or any other kind of sheet metal.

85 What I claim, and desire to secure by Letters Patent, is as follows:

90 1. In a metallic roof, the combination with the interlocking roof plates, of raised joint strips rigidly secured in position crosswise of the rafters underlying the lower margin of the upper member of each interlocking pair 95 of plates, and a metallic cleat embracing said strip and having both of its free ends interlocking with the upper marginal flange of the lower member of each pair of interlocking plates, substantially as described.

100 105 2. A metallic roof comprising interlocking copper-roof-plates, raised strips rigidly secured crosswise of the rafters, and underlying the lower margin of the upper member of each interlocking pair of plates, and copper 110 cleats embracing said strips and having their free ends interlocking with the upper margin or flange of the lower member of each pair of 115 said interlocking plates, whereby the roof-plates are securely held in position without the use of nails or screws on their shedding surfaces.

120 125 3. In a metallic roof, the combination with the interlocking roof plates of sheet metal, of the wooden joint strips of wedge shape in cross-section, rigidly secured to the framework of the roof, and underlying the lower margin of the upper member of each pair of roof plates, and sheet metal cleats embracing said strips and having their free ends spaced apart laterally and interlocking with the upper margin of the lower member of each of 130 said pair of plates, and the said roof plates having their joint flanges folded downward and backward against the vertical face of the said strips substantially as and for the purpose set forth.

4. The metallic roofing, comprising raised joint strips running crosswise of the face of the rafters, the tie-strips underneath the rafters parallel with the joint strips and bolted thereto through the rafters or frame-work of the roof, the roof-plates interlocking over the said joint strips with their fold or joint flanges closed against the backs of the strips, and the cleats embracing the joint strips and

interlocking with the said joint flanges, substantially as and for the purpose set forth.

In testimony whereof I affix my signature in presence of two witnesses.

JOSEPH TYRA.
